UNITED STATES PATENT OFFICE.

WILLIAM HUBERTZ, OF LA FAYETTE, INDIANA.

DITCHING-MACHINE.

1,152,893.

Specification of Letters Patent.

Patented Sept. 7, 1915.

Application filed December 21, 1914. Serial No. 878,382.

To all whom it may concern:

Be it known that I, WILLIAM HUBERTZ, a citizen of the United States, residing at La Fayette, in the county of Tippecanoe and State of Indiana, have invented a new and useful Ditching-Machine, of which the following is a specification.

This invention relates to ditching machines, and is more particularly designed as an improvement upon the structure disclosed in Patent No. 536,727, issued to me on April 2, 1895.

One of the objects of the invention is to provide an improved connection between the frame of the machine and the supporting wheels and to provide supporting wheels of novel form whereby a more efficient connection may be had between the wheels and the frame than has heretofore been possible where spindles or the like have been used.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

In the accompanying drawings the preferred form of the invention has been shown.

In said drawings:—Figure 1 is a front elevation of a portion of a ditching machine having the present improvements combined therewith. Fig. 2 is a side elevation of one of the supporting wheels. Fig. 3 is a section on line A—B Fig. 2. Fig. 4 is a perspective view of the brake lever. Fig. 5 is a detail view of one of the pivotal connections between the ditcher frame and the supporting structure. Fig. 6 is a detail view of another form of connection.

Referring to the figures by characters of reference 1 designates the frame of the ditching mechanism, a portion of the ditching wheel or excavator being indicated at 2. This mechanism constitutes no part of the present invention and can be of that type disclosed in my patent hereinbefore referred to or can be of any other form desired. It might be stated, however, that the frame 1 is provided with drums or windlasses 3 connected to cables 4 which, in turn, are extended through blocks 5 attached to the frame 1 and to side standards 6, there being

any suitable means provided for rotating the drums or windlasses so as thus to raise or lower the frame 1 relative to the sides or standards 6. Connected to the frame 1 adjacent the top thereof are oppositely disposed V-shaped links 7, the terminals of the links being outturned as at 8 and pivotally attached to the standard or side structure 6. Below each of the connections 7 is another connection 9 substantially W-shape and pivotally connected at two intermediate points to the frame 1 as shown at 10 while its terminals 11 and its other intermediate point 12 are pivotally connected to the side structure 6.

From the foregoing it will be apparent that by taking up the cables 4, the frame 1 can be elevated, thus causing the connections 7 and 9 to draw inwardly upon the side structure 6. When, however, the cables 4 are paid out, the connections 7 and 9 will swing downwardly at their inner ends thus lowering the ditching or excavating mechanism 2. The connections 7 and 9 serve to hold the side structure 6 constantly parallel with the ditcher or excavator 2.

Each of the side structures 6 is provided with a supporting wheel in the front of a ring 13 constituting the rim of the wheel and which ring has a continuous V-shaped groove 14 in the inner edge thereof. Side structure 6 is provided with a large wheel 15 which bears within the groove 14 and secured to the side structure is a cross bar 16 having smaller wheels 17 likewise extending into the groove 14. Thus it will be seen that the ring 13 is engaged at three points by the wheels 15 and 17 and is securely braced against lateral sagging while remaining at the same time free to rotate. A bracket 18 may be secured to the side structure, this bracket carrying a lever 19 having an angular head 20. One end of the lever is connected by a link 21 to an actuating lever 22 which, in turn, has a cable 23 attached to it and extending upwardly to a point where it can be readily actuated. By means of this structure, the lever 19 can be swung relative to the wheel so as to bring its head 20 within the groove 14 and operate both to clean the groove and retard the rotation of the wheel. In other words, lever 19 constitutes an efficient brake.

Attention is called to the fact that the wheels 17 are supported above the center of the ring 13 so that only the wheel 15 re-

ceives any of the weight of the machine, the wheels 17 merely serving to hold the ring 13 properly assembled with the wheel 15. Attention is called to the further fact that 5 wheel 15 bears upon the ring 13 at a point in advance of the point of contact of said ring with the ground so that forward movement of the structure is thus facilitated especially when the machine is moving uphill.

10 What is claimed is:—

1. In a machine of the class described, the combination with opposed side structures, a ditching frame interposed therebetween, and parallel connections between each side structure and the adjacent side of the ditcher frame, said connections being parallel, of a supporting wheel connected to each side structure, each wheel comprising a ring having a continuous interior groove, and spaced 15 wheels connected to the side structure and bearing within the groove.

2. In a machine of the class described, the combination with opposed side structures, a ditching frame interposed therebetween, and parallel connections between each side structure and the adjacent side of the ditcher frame, said connections being parallel, of a supporting wheel connected to each side structure, each wheel comprising a ring having a continuous interior groove, spaced 20 wheels connected to the side structure and

bearing within the groove, a lever mounted upon each side structure, a second lever fulcrumed adjacent to and actuated thereby, and an angular head carried by said second lever and shiftable into the groove to clear the groove, said head constituting a brake shoe.

3. In a machine of the class described, the combination with a side structure, of a ring 40 constituting a wheel rim and having a continuous V-shaped groove in its inner edge, a wheel upon the lower end of the side structure, a cross bar connected to the side structure, wheels journaled upon the ends of the 45 cross bar, all of said wheels projecting into said groove to hold the ring against displacement relative to the side structure, a bracket connected to said side structure and bar, a lever fulcrumed thereon, an angular head upon the lever and constituting means for cleaning the groove, said head likewise constituting a brake shoe, and means for actuating the lever to retard or stop the rotation of the ring about its center.

In testimony that I claim the foregoing as my own, I have hereto affixed my signature in the presence of two witnesses.

WILLIAM HUBERTZ.
